(57) **CLAIM**

The ornamental design for the hook component for a push-pull tool, as shown and described in the accompanying drawings.

DESCRIPTION

FIG. 1 is an isometric view of the hook component for a push-pull tool;

FIG. 2 is a front elevational view thereof;

FIG. 3 is a rear elevational view thereof;

FIG. 4 is a side elevational view thereof, the opposing side being a mirror image of FIG. 4;

FIG. 5 is a top plan view thereof; and,

FIG. 6 is a bottom plan view thereof.

The broken lines in the drawings illustrate the portions of the design that form no part of the claim.
